UNITED STATES PATENT OFFICE

153,807

DESIGN FOR A POLISHER

Clarence Karstadt, Glen Ellyn, Ill., assignor to
Birtman Electric Company, a corporation of
Illinois

Application June 1, 1948, Serial No. 146,707

Term of patent 14 years

(Cl. D9—2)

To all whom it may concern:

Be it known that I, Clarence Karstadt, a citizen of the United States, residing at Glen Ellyn, in the county of Du Page and State of Illinois, have invented a new, original, and ornamental Design for a Polisher, of which the following is a specification, reference being had to the accompanying drawings, following a part thereof, in which:

Fig. 1 is a top plan view of a polisher, showing my new design; Fig. 2 is a side elevation thereof; and Fig. 3 is a fragmentary end elevation thereof with the handle broken for convenience of illustration.

I claim:

The ornamental design for a polisher, as shown.
CLARENCE KARSTADT.
